US0D1043627S

(12) **United States Design Patent** (10) **Patent No.:** **US D1,043,627 S**
(45) **Date of Patent:** **** Sep. 24, 2024**

(54) **MICROPHONE**

(71) Applicant: **Audio-Technica Corporation**, Tokyo (JP)

(72) Inventors: **Shingo Suzuki**, Tokyo (JP); **Karin Maebashi**, Kanagawa (JP); **Sean Bryson**, Tokyo (JP)

(73) Assignee: **AUDIO-TECHNICA CORPORATION**, Tokyo (JP)

(**) Term: **15 Years**

(21) Appl. No.: **29/793,392**

(22) Filed: **Jun. 9, 2022**

(30) **Foreign Application Priority Data**

Dec. 10, 2021 (JP) 2021-027238

(51) **LOC (14) Cl.** **14-01**

(52) **U.S. Cl.**

(57) **CLAIM**

The ornamental design for a microphone, as shown and described.

DESCRIPTION

FIG. 1 is a front-side perspective view of a microphone; FIG. 2 is a rear side perspective view of the microphone; FIG. 3 is a front elevational view of the microphone; FIG. 4 is a rear elevational view of the microphone; FIG. 5 is a top plan view of the microphone; FIG. 6 is a bottom plan view of the microphone; FIG. 7 is a right-side elevational view of the microphone; FIG. 8 is a left-side elevational view of the microphone; FIG. 9 is a front-side perspective view of a microphone portion of the microphone, shown separately to show aspects of the design that are not visible when combined; FIG. 10 is a rear-side perspective view thereof; FIG. 11 is a front elevational view thereof; FIG. 12 is a rear elevational view thereof; FIG. 13 is a top plan view thereof; FIG. 14 is a bottom plan view thereof; FIG. 15 is a right-side elevational view thereof; FIG. 16 is a left-side elevational view thereof; FIG. 17 is a front-side perspective view of a microphone holder portion of the microphone, shown separately to show aspects of the design that are not visible when combined; FIG. 18 is a rear-side perspective view thereof; FIG. 19 is a front elevational view thereof; FIG. 20 is a rear elevational view thereof; FIG. 21 is a top plan view thereof; FIG. 22 is a bottom plan view thereof; FIG. 23 is a right-side elevational view thereof; and, FIG. 24 is a left-side elevational view thereof.

(Continued)

Portions of the microphone shown in broken lines form no part of the claimed design.

1 Claim, 24 Drawing Sheets
